G. R. HARDING,

Burglar Alarm.

No. 87,256.

Patented Feb. 23, 1869.

Inventor

GEORGE R. HARDING, OF MANCHESTER, VIRGINIA.

Letters Patent No. 87,256, dated February 23, 1869.

IMPROVEMENT IN BURGLAR-ALARM.

The Schedule referred to in these Letters Patent and making part of the same.

To all whom it may concern:

Be it known that I, GEORGE R. HARDING, of Manchester, in the county of Chesterfield, and State of Virginia, have invented a new and useful Improvement in Thief and Fire-Detectors; and I do hereby declare the following to be a clear and exact description of the nature thereof, sufficient to enable others skilled in the art to which my invention appertains, to fully understand and use the same, reference being had to the accompanying drawings of this specification, in which—

Figure 1 represents a section of a dwelling-house, showing my invention applied thereto.

Figure 2 is an end view of the detector.

Figures 3 and 4 are views of the interior of the detector, and illustrating the workings thereof.

Figures 5 and 6 are views of detached parts.

Similar letters of reference indicate corresponding parts in the several figures.

My invention is a novel device for detecting thieves and fire, and announcing their localities, whether in dwelling-houses, stores, pig-sties, henries, stables, or gardens, and in fact any place where a thief would be tempted to enter, or fire can occur.

It consists in applying, to either of the aforesaid places, a series of cords or wires, which, when the thief attempts to enter therein at any point, are tightened or drawn so as to operate suitable mechanism, and thus strike an alarm-bell, discharge a pistol, and strike a match, which lights a lamp.

The same result is produced when fire occurs. In this case the cords are liberated, but the operation is the same as before stated.

The locality of the attempted entrance of the thief, or the existence of the fire, will be readily announced by certain means, which, with what has been hitherto set forth, will be hereinafter more fully described.

In the drawings—

A may represent a section of a dwelling-house, constructed in the usual manner.

Within one of the rooms of the building is to be placed the detector B, whose construction and mode of operation will be presently explained.

C represents a cord or wire, which is passed entirely around the room, either in close proximity to the windows, or at such a distance as to be connected thereto by a hook, cord, chain, wire, or otherwise.

It passes the front door, but during the day-time it should be disconnected, so as to allow the opening of said door without disturbing said cord.

Each room will have one or more cords, so that when connected to the detector B, the raising of the window-sash, the opening of the door, or person entering a room, will draw the cord with it, and give the alarm, as will hereafter be explained.

The same result is produced if the cords are applied to the stable, chicken-house, or barn, around the corn-field, or other places.

D represents a latch-lock, for the inside of front, back, or other door.

It consists of a plate, E, of metal, hinged near its middle to ears z, to which is connected a rod or shank,

This shank is journalled in the door, and its end is formed with a square, whereby a key will readily turn it, so as to operate the latch D.

When a person leaves the house, and closes the door, he turns the latch, so as to prevent the opening thereof.

To one end of the hinged plate E, a cord is secured, so that should any one attempt to force open the door, the plate is partly swung from its position, so as to draw the cord with it, and thereby communicate with the detector.

The cords of each room will communicate separately with the detector, so that the locality of the attempted entrance may be readily announced.

It must be here observed that the cords will be stretched or held sufficiently taut as to be quite sensitive to the touch of any one who comes in contact with them, whereby alarm is sounded at all times.

B represents the detector. It consists of a suitable box or chamber, within which, and on top, are placed the alarms, and the mechanism for operating the same.

F is a frame, which is secured to the inside of the box, and adapted to support mechanism consisting of suitable clock-work.

In the present case, a shaft, G, is mounted on the frame F, and has secured to it a spring, which is adapted to be wound upon said shaft, through the medium of a proper key, the end of the shaft being formed with a square for said purpose.

On this shaft is keyed, or otherwise fastened, a pinion or spur-wheel, a, and a ratchet, b, bearing against the wheel. A spring-pawl bears against this ratchet, so as to allow the winding up of the spring without turning the pinion, but permit of its rotation with the shaft, on the unwinding of the spring.

There is nothing new in this mechanism. Equivalents may be employed, the object being to impart motion to the wheel a, and an escapement G.

To the shaft y of this escapement is secured a hammer, d, which receives a striking-motion from said escapement.

A bell, e, is placed within reach of the hammer, so as to be struck thereby.

To the frame, I pivot a lever, H, which has its ends free.

A spring, f, bears against the outer end, so as to continually force down the inner end.

On the upper side of the outer end there rises a conical-shaped stop, or cam J, which is in the form of a truncated cone, and slightly notched at the top.

A lever, K, is likewise pivoted to the frame F, and occupies a position that its lower end may be dropped into the notch, and prevent the movement of the lever H.

On the escapement-shaft, I attach a wire or stop, z, which shall project therefrom in the direction of the free end of the lever H, so as to come in contact with said end when the lever is in position, as shown in fig. 3, that is, when the bottom of lever K rests in the notch in the cone J.

Now, it will be perceived that when the lever K is

moved free from the lever *H*, the inner end of the latter is forced down, and clears itself of the stop *x* on the escapement-shaft.

The escapement is thus free to operate, and at once reciprocates, causing the hammer *d* to strike the bell *e*.

To the upper end of the lever *K* is attached a cord, *g*, which is likewise connected to a spring, *h*, and then passes out of the box, whence it is connected to the cord *C*, which has before been described.

It will now be readily understood that when the cords are pushed by the person who enters the house, the lever *K* is thrown away from the cone *J*, the escapement is free, the bell struck, and the alarm sounded.

L is a sliding rod, which passes partly into the box and extends partly above it. It is properly guided, and has secured to it a spring, which so bears upon it as to continually force it upward.

The upper end is formed with a match-holder, *M*, and a set-screw, *w*, to hold the match thereon.

A striking-plate, *N*, is placed on the top, in line with the match-holder, and is adapted to ignite the match by the upward motion of the rod.

A notch or catch is cut in the rod, into which drops one end of a dog, *O*, which is pivoted to the frame *E*.

A lug or pin, *v*, is formed on the spur-wheel *a*, and is adapted to bear against the dog *o*, and force it out of the notch, thereby releasing the rod, and allowing it to fly upward.

The rod must be forced down to its lowest position before it will be caught by the dog.

If a match is placed on the rod, and brought against the striking-plate *N*, the upward motion will cause an immediate ignition of the match.

A trigger, *P*, is suspended within the box, and is pivoted thereto, so that its lower end will come in contact with the pin *v* on the wheel during the rotation of said wheel.

The upper end of said trigger is in line with the spring-dog *Q* of a pistol, *R*, which is mounted on the box. This pistol is of ordinary construction, and has a nipple for the cap, and an extension at the rear, to which the dog is pivoted.

The hammer *S* of the pistol consists of a flat piece of steel, connected at one end in any suitable manner to the box, or to the metallic piece to which the barrel is attached.

The under side of the front end of the hammer has a lug, *t*, which is to strike the cap placed on the nipple beneath it.

A pin, *s*, projects downwardly from the hammer, and is formed with a shoulder, *r*, (see fig. 3,) under which the spring-dog catches, and holds the hammer cocked and ready to be discharged. When the hammer is raised, the dog drops under the shoulder of the pin.

The trigger will be moved by the pin *v* on the toothed wheel, and thereby force the dog away from the pin *s*. The hammer immediately springs, and snaps the cap, and discharges the pistol, should it be loaded.

A lamp, *T*, is placed or secured on top of the box, and the burner or wick extends at an angle to the reservoir.

The wick must be placed directly above the end of the match, or sufficiently near to be lighted by the ignition of the match.

So soon as the stop of the escapement is free, the mechanism sets to work, the bell is then rung, the pistol discharged, or its cap snapped, the match ignited, and the lamp lighted. These results occur successively, and while they alarm the occupants, and frighten off the thieves, they furnish ready light, which is very desirable in such cases.

In case of fire in either of the rooms of the house, or the other places to which the detector is applied, a result similar to the above is produced.

Owing to the tautness of the cord, and the attachment thereto of the spring *h*, it is evident that should the cord burn, the lever *K* will be thrown free of the cone *J*, the mechanism thereby start, and the various operations be as before stated.

Another feature of my invention is an indicator, or means for announcing in what part of the house the entrance was attempted or the fire occurred.

For this purpose, the number of cords communicating with the detector must be equal to the number of rooms or places to which the detector is applied.

These cords are passed through openings in a plate on the end of the box, or through the end itself. (See fig. 2.)

Suitable numbers, characters, or names will be made over or round the opening, so as to indicate the number or name of the room, stable, henry, or otherwise.

Whatever cord is moved or burnt will show itself by the looseness it displays. According to the opening through which the loose cord runs, so is the locality of the thief or fire.

In order to render the detector inoperative, as in day-time, I apply a holding-device to the lever *K*.

A small rod projects laterally from the top of this lever, extends outside of the box, where it is provided with a handle, *o*, and moves in a curved slot in the side of the box.

It is evident that the lever *K* may be readily operated, so as to bear against the top of the cone *J*, and thereby stop the mechanism at any moment.

The rod at the top of lever *K* is straddled by forks *p*, which are connected to a turning-rod, *U*, arranged in the upper part of the box.

A portion of the rod is on the outside of the box, so that it can be easily turned.

A finger, or pointer, is secured near the outer end of the rod, and sweeps over a plate secured to the box.

This plate has an arrow engraved or formed thereon, which is merely to point the proper direction for turning the rod.

Fig. 3 will show the relative position of the forks and finger. When the finger points upward, the forks are down, and straddle the rod of the lever *K*, thereby preventing the movement of said lever, but when the rod is turned toward the left, the finger follows it, but the forks turn to the right, and clear said lever-rod. In the latter case, the lever is ready for operation, and may then be moved from its state of rest by drawing, pulling, breaking, or burning of the cords.

The detector should be placed at night in the sleeping-chamber, but in the early part of the evening it may be in the parlor, sitting, or dining-room, or wherever some members of the family may be, in order to hear or see the operation of the device.

The cords or wires *E* may be concealed in any well-known manner, and arranged properly, so that they are always in close proximity of shutters, windows, sky-lights, cellar-doors, trap-doors, gates, fences, and whatever places are to be protected.

Should any one bore through the wall, window-shutter, or otherwise, or an arm be inserted through, it is intended that the tool or arm shall strike the cord or wire, and sound the alarm, the same as if either were actually pushed or pulled by the intruder.

The various applications of my invention are numerous. It is alike simple, practical, and useful.

Having thus described my invention,

What I claim as new, and desire to secure by Letters Patent, is—

1. The cam *J*, on the spring-lever *H*, the releasing-lever *K*, the cord *C*, and the escapement-stop *x*, combined and operating substantially as described.

2. The latch *D E*, constructed and operating as and for the purpose set forth.

3. The lug *v*, on wheel *a*, the suspended trigger *P*, the dog *O*, and the shouldered pin of the spring-hammer *S*, arranged and operating as described.

To the above, I have signed my name, this 16th day of October, 1868.

G. R. HARDING.
